CLAIM

We claim the ornamental design for the street furniture, as shown and described.

DESCRIPTION

FIG. 1 is a perspective view of the street furniture according to the design;

FIG. 2 is a side elevational view of one side of the street furniture;

FIG. 3 is a side elevational view of another side of the street furniture; and,

FIG. 4 is a top plan view of the street furniture of FIG. 1, the bottom plan view being the same.

The side not shown is identical to the side shown in FIG. 3.
